UNITED STATES PATENT OFFICE.

ROBERT JACOBS, OF BOSTON, AND IRVING WILLIAM JACOBS, OF BROOKLINE,
MASSACHUSETTS.

GAME.

Application filed February 19, 1927. Serial No. 169,511.

This invention relates to games to be played with specially designed cards and a circular dial board having a pointer at its centre to be revolved.

5 The invention will be hereinafter considered in detail and specifically claimed. Reference will now be had to the drawing forming a part of this application, wherein there is illustrated a preferred embodiment of our invention, but it is understood that the elements thereof can be varied or changed as for shape, size, or form without departing from the spirit of the invention.

In the drawing:

15 Fig. 1 is a view of the dial board or chart with the pointer mounted at its centre.

Fig. 2 is a view of a card from a pack that is used in combination with the chart and pointer.

20 Fig. 3 is a view of another card used, with the chart and pointer.

The game may be played by any desired number ranging from two to eight persons. The chart is divided into 8 circles, numbered 25 1 to 8, consecutively. These circles are divided into a number of sections corresponding to their numbers. That is circle number 8 is divided into eight sections, circle number 7 is divided into seven sections, etc.

30 The centre of the circles is provided with a pivot 10 on which there is pivotally mounted a pointer 11.

There are five sets of playing cards numbered from 1 to 10, or cards that have from 35 one to ten zeros on it, a sample of which is shown in Fig. 2, making it fifty cards and three extra cards on which there is a large zero, as shown in Fig. 3, making it a total of fifty three cards.

40 We will now describe the method of playing this game.

The players are grouped around the chart and they sit opposite the number that corresponds to the number of players. That is 45 if there are eight players, they sit opposite the numbers eight, and they each have their sections, between the lines 8—8. If there are seven players, they each sit opposite the lines designated by number 7 and have each 50 a section between lines 7—7, etc. Five cards are dealt, one at a time to each player and are turned face up by the dealer.

As each of the first two rounds are dealt, the dealer announces its number. This goes 55 on for two rounds only, and these numbers

only are taken in consideration when figuring the total number of points lost or won. The remaining three rounds are dealt silently, and do not figure in the total number of points lost or won.

60 Any player receiving a "zero" card during five rounds of this set, i. e., a card shown in Fig. 3, is exempt from having his numbers figured in the case of loss, by him during this particular set of five rounds.

65 During the five rounds, of each set, three possible combinations may occur.

Combination 1.

A player may receive two "zero" cards 70 during one set of five rounds. When this occurs, he is credited with the total of all the numbers of all the other players that are shown, without a spin of the pointer.

Combination 2.

If none of the players get two "zeros," then the player whose hand totals fifteen points or less, wins the set and is credited with the total number of points of all the players, without a spin of the pointer. But if two or more players have the same number of points, then the holder of a "zero" card or if there is no holder of a "zero" card, then the holder of the lowest card 85 wins.

Combination 3.

When neither combination 1 nor combination 2 occurs, then the pointer is spun. The 90 section in which the pointer stops decides the winner, whereupon that player is credited with all the number of points on the board.

Having described our invention, what we 95 claim is:

1. As a new article of manufacture, a card deck containing five sets of ten cards each on which there appear zeros, numbering from one to ten, and three cards on which single large zeros appear.

2. In combination with a card deck containing five sets of ten cards each, on which there appear zeros, numbering from one to ten, and three cards on which single zeros, 100 a dial divided into segments and into circles, and a pointer at its centre.

ROBERT JACOBS.
IRVING WILLIAM JACOBS.
